UNITED STATES PATENT OFFICE.

JOSEPH HORN, OF WEST ORANGE, FERDINAND H. MAY, OF MONTCLAIR, AND JOSEF MEILNER, OF WEST ORANGE, NEW JERSEY.

ALARM.

1,392,568.

Specification of Letters Patent.

Patented Oct. 4, 1921.

Application filed February 26, 1921. Serial No. 448,274.

To all whom it may concern:

Be it known that we, JOSEPH HORN, a citizen of the United States, and resident of West Orange, county of Essex, State of New Jersey, FERDINAND H. MAY, a citizen of the United States, and resident of Montclair, county of Essex, State of New Jersey, and JOSEF MEILNER, a citizen of Germany, and resident of West Orange, county of Essex, State of New Jersey, have invented certain new and useful Improvements in Alarms, of which the following is a specification.

Our invention relates to alarms and more particularly to theft or burglar alarms intended to prevent the theft or illegitimate use of automobiles and other motor-driven vehicles and has for its object the provision of a novel alarm of this type which is simple in construction, efficient in operation and which cannot readily be rendered inoperative by unauthorized persons and whereby an attempted theft or unauthorized use is audibly announced and thereby frustrated. Other more specific objects will appear from the description hereinafter and the features of novelty will be pointed out in the appended claims.

In the accompanying drawings, which show an example of our invention without defining its limits, Figure 1 is an elevation illustrating the alarm in operative connection with a cylinder of an internal combustion engine; Fig. 2 is a sectional elevation on the line 2—2 of Fig. 1; Fig. 3 is a plan view; Fig. 4 is a horizontal section on the line 4—4 of Fig. 2; Figs. 5 to 10 inclusive are detail views illustrating parts of the locking mechanism; Fig. 11 is a diagrammatic, sectional view illustrating another arrangement of the invention; and Fig. 12 is a fragmentary sectional view on the line 12—12 of Fig. 11.

In its illustrated form, the alarm comprises a base 10 having an externally screw-threaded neck 11 whereby connection with the head 12 of a cylinder 13 of an internal combustion engine is effected, the location of the device on said cylinder being preferably in close proximity to the spark plug 14 or other ignition device thereof. The base

10 is formed with outwardly diverging passages 15 which communicate with an axial passage 16 in the base and terminate at their exit ends in an annular recess 17 of relatively reduced width formed in the face 55 of said base, as shown in Fig. 4, the axial passage 16 in turn leading to the interior 18 of the neck 11 whereby communication with the combustion chamber 19 of the cylinder 13 is provided. A sounding cup 20 of 60 suitable material and construction is fitted between oppositely disposed supports 21 fixed upon or comprising integral parts of the base 10 and is secured in position in registry with the annular recess 17 in any suitable manner as by means of screws 22. In order that the sounding cup 21 may be adapted to the different degrees of compression found in the various types of motors in common use, it is preferred to provide 70 for the adjustment of said cup in axial directions toward and away from said recess 17; this adjustment may be effected in any convenient manner as, for instance, by providing the supports 21 with one or more 75 slots 23 for the accommodation of the screw or screws 22 as shown in Fig. 2.

The supports 21 carry a disk 21^a upon which a housing 24 of the required dimensions and form is mounted for the accommodation and inclosure of a lock which is preferably of the combination type and in its illustrated form comprises a dial 25 rotatable upon the housing 24 and in surface engagement therewith, said dial having suitable designations 26 produced theron in the customary manner and adapted for co-operation with a suitable designation 27 upon the housing contiguous to the periphery of said dial, in the manipulation of the lock. The dial 25 may also be provided with a preferably knurled head or knob 28 to facilitate the rotation thereof and in addition, is formed with a sleeve 29 extending axially therefrom through a suitable opening into 95 the housing 24, as shown in Fig. 2. Any suitable means may be utilized for maintaining the dial 25 and its correlated parts against separation from the housing 24 without interfering with the rotative movements 100

of said dial relatively to said housing; for instance, as shown in the illustrated example, one or more screws 30 may extend radially through the housing 24 into an annular groove 31 formed in the sleeve 29.

In addition to the elements so far described, the illustrated locking mechanism comprises an operating disk 32 which is fixed upon the sleeve 29 to rotate therewith within the housing 24 and a pair of lock-disks 33 and 34 rotatably mounted upon said sleeve within the housing and upon opposite sides of the operating disk 32 in surface engagement with the opposite faces thereof as shown in Fig. 2. The operating disk 32 is provided on one surface with a stud 35 adapted for cooperation with a series of apertures 36 formed in the lock-disk 33 and with a stud 35^a arranged to travel in an annular groove 37 of the lock-disk 34 and to cooperate with a projection 38 in said groove, as will be more fully explained hereinafter. The lock-disks 33 and 34 are provided with peripheral notches or recesses 39 and 40 respectively, arranged to be brought into registry with each other in the manipulation of the lock and to receive the latch 41 of a bolt 42 slidably mounted by means of screws 21^b upon the disk 21^a within the housing 24; suitable openings 43 and 44 are provided in the latter to permit the necessary movements and operation of the combined latch 41 and bolt 42. The bolt 42 includes an opening 42^a, the periphery of which, at least at one point, comprises a locking member 42^b, preferably formed with opposite cam surfaces, as shown in Fig. 2. In the illustrated example, the lock includes further a lever 45 pivoted at 46 upon the casing 18 and carrying a counter-weight 47 whereby the lever is maintained in engagement with the bolt 42 and the latter is always automatically moved into its locking or operative position at the proper time; the support 21 is formed with a slot 48 in which the lever 45 is mounted, as shown in Fig. 2.

The alarm in addition includes means whereby it may be rendered inoperative by an authorized person or set in an operative adjustment to frustrate an attempted theft or an unauthorized use of the vehicle in which the alarm is installed, said means being securely locked against tampering in either position by the locking means previously described. In the illustrated example, this means comprises a stem 49 slideable in the base 10 and including an enlargement 50 slideable in an axial bore 51 of the sleeve 29 as shown in Fig. 2, said stem carrying a valve 52 arranged to open and close the end of the axial passage 16 to establish and cut off communication between the combustion chamber 19 and the sounding cup 20. The stem 49 passes through the opening 42^a of the bolt and through a suitable open-

ing in the disk 21^a and carries a double cam 53 arranged to coöperate with the cam surfaces of the locking member 42^b to shift the bolt 42 and more particularly the locking member 42^b thereof transversely to permit an authorized adjustment of the stem 49 and with it the valve 52; the double cam 53 and locking member 42^b coöperate also to lock the valve 52 in either of its positions when the bolt 42 and latch 41 occupy an operative position.

In order to prevent tampering with the operative parts of the alarm, it is preferred to include a main cover 54 which sets over and incloses the housing 24, the supports 21 and their correlated parts, and which includes a recessed base 55 arranged to fit over and receive the base 10; unauthorized removal of said cover 54 is also prevented by the lock previously described, the bolt 42 of which includes a lug 42^c which enters an annular groove 54^a located at the proper point upon said cover 54. The latter, as shown, may be constructed in the form of a cage provided with a plurality of ribs 56 located at spaced intervals throughout said cover 54 and forming between them a plurality of apertures 57 through which the sound waves set up by the action of the combustion or other gases upon the sounding cup 21 freely pass without being muffled to any appreciable degree; the arrangement of ribs 56 and apertures 57 is such that access through the latter to the alarm for the purpose of tampering therewith or for any other reason is impossible.

For the purpose of reducing to a minimum the possibility of having the alarm rendered inoperative or deficient for its intended purpose, a device may be included therein which coöperates with the ignition device whereby the charge is ignited, to prevent removal of said device from the cylinder; for instance, as shown, the cover base 55 may be constructed with an auxiliary cover 59 forming an integral part thereof or otherwise permanently connected therewith and arranged to set over the spark plug 14 near which the alarm is located. The auxiliary cover 59, when in operative position, by reason of its construction, prevents removal of said spark plug 14 which, if accomplished, would provide an escape opening for the combustion gases or other fluid and a consequent reduction in the pressure exerted upon the sounding cup 21 whereby the sounding of the alarm might be weakened to such an extent as to become inefficient for its intended purposes.

In describing the operation of the alarm, it will be assumed that it is installed upon one of the cylinders 13 of an engine which constitutes the motive power of an automobile, the cylinders being upright and the alarm projecting upwardly from the head 130

12 of said one cylinder 13, for instance, as shown in Figs. 1 and 2. It will, of course, be understood that this is only an example chosen for the purposes of illustration and 5 description and that the limits of the invention are not defined thereby. In the normal, inoperative condition of the alarm, the stem 49 occupies a raised position in which it is held by means of the locking member 42^b 10 of the bolt 42, which projects beneath the double cam 53, the valve 52, in this case, closing the end of the passage 16 and thereby cutting off the communication between the combustion chamber 20 and the alarm. 15 The bolt 42, with its locking member 42^b, is held in the described position by the action of the lever 45 under the influence of the counter-weight 47 and is locked against movement in an unlocking direction 20 to cause one or both of the disk notches 39 and 40 are out of registry with the latch 41, the peripheries of said disks acting as stops to prevent inward movement of said latch, as will be readily apparent. 25 When it is desired to set the alarm in an operative position, the lock-dial 25 is rotated first in one direction through the medium of the knob 28 until a predetermined designation 26 registers with the designation 30 27 and then in the opposite direction until a second predetermined designation 26 on the dial 25 registers with the designation 27 on the housing 24. This actuation of the dial brings about an adjustment of the lock-disk 33 and 34 through the medium of the operating disk 32, in which the notches or recesses 39 and 40 are brought into registry with each other and with the latch 43. In other words, a movement of the dial 25 to 40 the right will, because of the connection between the operating disk 32 and lock-disk 33 through the medium of the stud 35 and one of the apertures 36, carry the disk 33 along. This movement is continued until 45 the predetermined designation 26 is in registry with the designation 27 which brings the notch 39 of the disk 33 into registry with the latch 43, it being understood that the described actuation is relatively to the lock-disk 34 which remains approximately stationary, the stud 35^a traveling in the annular groove 37. After the disk 33 has been set, a movement of the dial 25 to the left will finally cause the stud 35^a of the operating 50 disk 32 to engage the projection 38 of the lock-disk 34 whereupon a continued rotation of the dial will carry along the disk 34 until the predetermined designation 26 is in registry with the designation 27 which 55 brings the notch 40 into registry with the notch 39 and with the latch 43. The combination may be changed by simply setting the stud 35 in different apertures 36 of the lock-disk 33. The stem 49 may now be 60 pushed downwardly to move the valve 52 away from the end of the passage 16, the bolt 42 being shifted to the left in Fig. 2 by the action of the double cam 53 upon the locking member 42^b and the latter being thus moved out of the path of said double cam; 70 the lug 42^c partakes of this movement of the bolt and is consequently withdrawn from the groove 54^a of the cover 54 whereby the latter may be unlocked for removal at any time. The described movement of the bolt 75 is possible because of the fact that the registering notches 39 and 40 of the disks 33 and 34 provide the space necessary to permit the latch 43 to partake of the movement in question. In other words, the obstruction interposed by the peripheries of the disks to an inward movement of the latch 43 is removed by the previously described manipulation of the lock. As soon as the downward movement of the stem 49 is sufficient to 80 bring the double cam 53 beyond the member 42^b, the bolt 42 is shifted to the right in a return movement, under the influence of the lever 45 and the counter-weight 47 and thus brings the locking member 42^b above the 85 double cam 53 and coincidentally moves the latch 41 out of the notches 39 and 40. By suitably manipulating the dial 25 in a predetermined manner at this stage, the disks 33 and 34 may be actuated to shift one or 90 both of the notches 39 and 40 out of registry with the latch 41 and thus lock the same against any material movement in an inward direction. As a result, it is impossible for anyone unfamiliar with the combination of the lock to release the stem 49 so that the valve 52 is securely fastened in a position in which the channel 16 is open and communication between the combustion chamber 20 and the chamber 17 is unobstructed. If any attempt is now made to 100 operate the engine, the gaseous fuel or the combustion gases will pass from the cylinder 13 through the interior 19 of the neck 11, the passage 16 and channels 15 and out of the annular recess 17 in a circular stream which acts upon the sounding cup 21 and operates the alarm, for instance, in a succession of blasts, the frequency of which depends upon the speed at which the engine is being run. It is therefore impossible to drive the automobile in which the alarm is installed, without giving notice thereof, so that apprehension of the thief or of an unauthorized user of the vehicle becomes a 110 115 foregone conclusion. 120 To bring the alarm to an inoperative condition, the dial is again manipulated to release the locking mechanism, and to permit the stem 49 to be raised whereby the valve 52 is caused to close the passage 19 and the locking member 42^b is moved beneath the double cam 53 to fix the stem and valve in their raised positions. Another manipulation 125 of the dial 25 again locks the mechanism 130

and the various elements against unauthorized adjustment. Communication between the combustion chamber 20 and the chamber 17 having been cut off, the engine is now 5 free to be operated without sounding the alarm.

For the purpose of setting the alarm directly from the chauffeur's seat and in order to avoid the necessity for having access to 10 the alarm itself and to reduce to the utmost simplicity the operation of adjusting the alarm, an arrangement such as is diagrammatically illustrated in Fig. 11 may be utilized. In this case, the dial 25 is either provided 15 with bevel-toothed periphery or with a bevel gear 25^a which meshes with a co-operating bevel gear 60 mounted, for instance, upon a stub shaft 61 journaled in a bracket bearing 62 carried by or forming an 20 integral part of a ring clamp 63 which is clamped upon a suitable part of the cover 54 as shown in Fig. 11. A sleeve 64 is slidably mounted upon the shaft 61 and is 25 slidably connected therewith, for instance, by means of a pin 65 and a slot 66 which serve also to couple the sleeve 64 to the shaft 61 and consequently to the gear 60. The sleeve 64 further carries a disk 67 and is 30 flexibly connected with a shaft 68 by means of a universal joint 69 of any convenient type, said shaft 68 in turn projecting through and being slidably and rotatably mounted upon the instrument-board 70 of the vehicle in which the alarm is installed. 35 At its free end, which is on that side of the instrument-board facing the driver of the vehicle, the shaft 68 may carry a pointer 71 arranged for co-operation with a dial 25^b which may be a duplicate of the dial 25 in so far as designations 26^a are concerned, and may be provided also with an operating head 40 or knob 72. The arrangement being described may further include a bell-crank lever 73 pivoted at 74 upon a lug carried by 45 the ring clamp 63 and having its one end forked at 75 for connection with the head 49^a of the stem 49 and its other end pivotally connected at 76 with one end of a lever 77 which is itself slidably mounted by 50 means of a pin 78 and slot 78^a upon the bracket bearing 62 of the ring clamp 63. The other end of the lever 77 is forked at 55 79 for connection with the periphery of the disk 67 which is of suitable form to permit rotation of said disk relatively to said forked end 79.

In practice, a rotation of the pointer 71 relatively to the dial 25^b by means of the knob 72 will rotate the shaft 68 and sleeve 64, motion being transmitted through the medium of the universal joint 69 and being communicated by means of the pin 65 and slot 66 to the shaft 61 and to the bevel gear 60 which in turn actuates the co-operating gear 25^a. The movements of the latter will

thus be duplicates of the pointer 71 and consequently will actuate the dial 25 in the same way as previously described and thus operate the locking mechanism in the same way as hereinbefore set forth; after the locking mechanism has been manipulated in the pre-determined manner, a pull is exerted upon the head or knob 72 which is transmitted, by means of the shaft 68, to the sleeve 64 and causes the latter to move lengthwise of the shaft 61, the disk 67 partaking of said movement of the sleeve 64. The described linear actuation of the disk 67 causes the lever 77 to slide in the bracket bearing 72 within the limits of the slot 78^a and rocks the bell-crank 80 lever 73 which accordingly exerts a pull or a push upon the head 49^a, according to the direction of operation, and thereby shifts the rod 49 to open or close the valve 52 in exactly the same way and for the same reasons 85 as hereinbefore described.

The knob 72 being located within easy reach of the driver or operator of the vehicle, the actuating of the mechanism necessary to adjust the alarm to its operative or 90 inoperative condition is reduced to the utmost simplicity and may be accomplished with a minimum of effort and without requiring any access to be had to the motor or to the alarm itself. 95

In all of its forms, the invention provides a lock-protected alarm-signal of simple construction and efficient operation whereby an attempted theft or unauthorized use of automobiles and other motor-driven vehicles may 100 be positively and quickly frustrated. The device is arranged to produce an alarm in the nature of a whistling sound, which is very penetrating and of distinctive character and which may readily be distinguished 105 from all customary and usual traffic signals, even under the most crowded traffic conditions and is thus certain to quickly attract the attention of police officers and others. The discovery of the offender and his apprehension is therefore practically certain as it is impossible to silence the alarm, once it is in its operative adjustment, without first actuating the locking mechanism and correlated parts or by stopping the motor. The locking mechanism, in its illustrated form, is entirely without springs and other delicate parts likely to become injured by the high temperature of the combustion gases or other effects thereof, or by expansion and contraction due to rapid changes in temperature conditions in the vicinity of the alarm. As a matter of fact, the locking mechanism is protected from the effects of excessive heat by that part of the interior 125 of the casing which is between the housing and the sounding cup and which constitutes an air-chamber.

By adjusting the sounding cup toward and away from the annular recess 17, the 130

alarm is adaptable to all makes of motors regardless of the degree of compression generated therein.

Various changes in the form shown and 5 described may be made within the scope of the claims without departing from the spirit of our invention.

We claim:

1. An alarm of the kind described comprising a support having an inlet for an actuating fluid, a valve controlling the same, a sounding device carried by said support and arranged to be actuated by said fluid, a housing mounted upon said support 15 and locking means within said housing whereby said valve is locked against tampering in either its open or its closed position and means mounted exteriorly upon said housing for actuating said locking means.

2. An alarm of the kind described comprising a support having an inlet for an actuating fluid, a valve controlling the same, a sounding device carried by said support and arranged to be actuated by said fluid 20 and adjustable toward and away from said inlet, a housing mounted on said support, locking disks within said housing whereby said valve is locked in either its open or its closed position, an operating disk within 25 said housing for operating said locking disks, dial mechanism mounted exteriorly upon said housing for actuating said operating disk, and a cover fitted over said housing and support to inclose the same.

3. An alarm of the kind described comprising a support, a base connected with said support and having an annular outlet leading to the interior of said support, an inlet and diverging channels communicating with said inlet and with said outlet, a housing mounted on said support, a sounding device on said support, a valve controlling said inlet, a slideable stem carrying said valve and arranged to open and close the same, and locking mechanism within said housing coöperating with said stem to lock said valve in an adjusted position.

4. An alarm of the kind described comprising a support, a base connected with 50 said support and having an annular outlet, an inlet and diverging channels communicating with said inlet and with said annular outlet, a housing mounted on said support, a sounding device on said support and 55 adjustable toward and away from said outlet, a valve controlling said inlet, a slideable stem carrying said valve and arranged to open and close the same, a double cam mounted on said stem, a bolt in said housing 60 coöperating with said double cam to lock said stem against movement and thereby fix said valve in an adjusted position, a weighted lever whereby said bolt is maintained in and returned to its locking position, locking 65 mechanism within said housing, a latch car-

ried by said bolt and coöperating with said locking mechanism to lock the bolt against movement, means, located exteriorly of the housing, for manipulating said locking mechanism and an apertured cover fitted 70 over said support, base and housing to inclose the same.

5. The combination with the cylinder of an internal combustion engine and an ignition device connected therewith, of an 75 alarm connected with said cylinder and operated by gaseous fluid therefrom, means for selectively controlling the connection between said cylinder and the alarm locking mechanism whereby said means is locked in 80 an adjusted position and connected devices whereby said alarm is protected against tampering and said igniting device is locked against removal from the cylinder.

6. The combination with the cylinder of 85 an internal combustion engine and an igniting device connected therewith, of an alarm mounted upon said cylinder and operated by gaseous fluid therefrom, means for selectively controlling the connection between 90 said cylinder and the alarm, locking mechanism, whereby said means is locked in an adjusted position, an apertured cover fitted over said alarm and inclosing the same and an auxiliary device permanently 95 connected with said apertured cover and co-operating with said igniting device to prevent removal of the latter from said cylinder.

7. The combination with the cylinder of 100 an internal combustion engine and a spark plug carried thereby, of an alarm mounted upon said cylinder and operated by gaseous fluid therefrom, a valve controlling the connection between said cylinder and the alarm, means for operating said valve to open or 105 close said connection, a combination lock co-operating with said operating means to lock said valve in an adjusted position, a main cover fitted over said alarm and provided 110 with apertures for the escape of the sound waves produced by said alarm, and an auxiliary cover permanently connected with said main cover and extending over said spark plug to prevent its removal from said 115 cylinder.

8. The combination with the cylinder of 120 an internal combustion engine of an alarm connected with said cylinder and operated by gaseous fluid therefrom, means for selectively controlling the connection between said cylinder and the alarm, locking means whereby said controlling means is locked in an adjusted position against tampering and mechanism including an actuating device located at a distance from said alarm and adapted to actuate said locking means and to also operate said controlling means.

9. In a motor-driven vehicle including an 125 instrument board and a driving motor, the 130

combination of an alarm connected with said motor to indicate unauthorized operation thereof and including slidable means for controlling said alarm, and rotatable locking means for locking said slidable means in an adjusted position, and mechanism extending to said instrument board and operatively connected with said controlling and locking means, said mechanism being capable of both

sliding and rotative movements to correspondingly actuate said slidable means and locking means respectively. 10

In testimony whereof we have hereunto set our hands.

JOSEPH HORN. [L. S.]
FERDINAND H. MAY. [L. S.]
JOSEF MEILNER. [L. S.]
